UNITED STATES PATENT OFFICE.

CARL WEGENER, OF BERLIN, GERMANY.

SMOKELESS COMBUSTION-FURNACE.

SPECIFICATION forming part of Letters Patent No. 711,805, dated October 21, 1902.

Application filed October 17, 1900. Serial No. 33,389. (No model.)

To all whom it may concern:

Be it known that I, CARL WEGENER, a subject of the King of Prussia, Emperor of Germany, residing at Nos. 14 and 15 Gitschinerstrasse, Berlin, Prussia, German Empire, have invented new and useful Improvements in and in Connection with Smokeless Combustion - Furnaces, of which the following is a specification.

10 My invention relates to improvements in and connected with that class of furnaces in which the fuel is fed from underneath below an upper layer of burning fuel. In this class of furnaces the heating-gases are generated 15 by a perfectly-smokeless combustion as the fresh fuel introduced underneath that already burning is subjected to a preliminary heating from above, so that its products of distillation are completely oxidized as they 20 pass through the burning layer.

The object of my invention is to secure by the general arrangement of the furnace and by the way of supplying the air of combustion to the different zones of the burning fuel 25 a better combustion and a better utilization of the calorific value of the fuel.

In the accompanying drawings I have shown how my said invention may be conveniently and advantageously carried into 30 practice.

Figure 1 is a side elevation, partly in section, and Fig. 2 is a plan view, partly in section, of a furnace constructed in accordance with my invention. Figs. 3 and 4 are detail 35 views of the feeding device.

Throughout the drawings like reference-numerals refer to like parts.

The furnace constructed according to my invention consists in a combustion-chamber 1, the cross-section of which may be of any 40 suitable shape, having a sole which slopes toward the flue 2. In the walls of this combustion-chamber I provide inlets 3 for the admission of air, which are connected to a fan 45 5 by wind-passage 4.

I arrange in the sole of the combustion-chamber a pipe 6 for feeding in the fuel, and between the combustion-chamber 1 and the flue 2 I provide a trough 7 for collecting the 50 clinker and ashes. By means of the doors 8 and 9 the trough may be emptied and the fire in the furnace kindled. In the feeding-pipe

6 is arranged a hopper 11, with a slide 10 for filling the pipe 6 with fuel, and at the end of the feeding-pipe is the apparatus for introducing the fuel into the combustion-chamber. This apparatus consists in a piston 12, capable of being moved to and fro inside the pipe 6 and having attached to it a tube 13 for the screw-spindle 15, which rotates in the 60 pedestal 14. The said spindle is guided in the tube 13 by a ring 16 at its extremity. (See Fig. 1.) At the end of the tube is a guiding-head 17, with three slide-blocks 18, operated by a ring 19 with eccentric grooves 65 in such a manner that the blocks, the inner ends of which are provided with screw-threads, are thrown in or out of gear with the screw-spindle 15.

Attached to the ring 19 is the reversing-lever 21, provided with counterweight 20, which lever in the two extreme positions of the piston strikes against oblique stops 22 and 23, respectively, whereby the ring 19 is turned and the slide-block brought in or out of engagement with the screw-spindle. 70

The rotation of the screw-spindle is effected in the following manner: The shaft of the fan 5 carries a worm 24, meshing with worm-wheel 25, which actuates a connecting-rod 26. 80 The latter imparts a reciprocating motion to the rod 27, provided at its extremity with a projection and sliding on the surface 28 of the bearing-block 14. The screw-spindle 15 is fitted with a ratchet-wheel 29, which is rotated by a lever 32, provided with pawl 30 and a roller 31, which can move on rod 27. The projection at the end of the rod 27 striking against the end of the lever 32 brings the pawl 30 into engagement with the ratchet-wheel, whereby this accomplishes a partial rotation. On the return movement of the rod 27 lever 32 is brought back to its initial position by a spring 43, Fig. 4. 85

The stroke of rod 27, and consequently the 90 amount of rotation of the ratchet-wheel 29 of the screw-spindle 15 and consequently the feed of the fuel, can be regulated by a set-screw 33 and hand-wheel 34, Fig. 4. The piston 12 is returned to its normal position by a 100 counterweight 35, Fig. 1, as soon as slide-blocks 18 are by means of reversing-lever 21 thrown out of gear with screw-spindle 15.

The above-described furnace is operated as

follows: The pipe 6 is filled with fuel from the hopper 11 in such a manner that a small heap is formed above the opening of the said pipe in the combustion-chamber. The small 5 heap is covered with an easily-combustible material and then kindled. When the fire burns properly, the fan is set to work, care being taken to have only a slight blast at the start, the fan actuating at the same time the 10 feeding device, whereby fresh fuel is fed underneath that which is already burning. The firing is controlled by regulating the fan and the quantity of fuel fed by means of the hereinbefore-described feeding device. The slide 15 10 of hopper 11 is connected to the guiding-head 17 of tube 13 in such a manner that said slide is withdrawn and the fuel discharged into pipe 6 as soon as piston 12 has on its return travel passed the opening of the hopper. 20 What I claim, and desire to secure by Letters Patent of the United States, is—
1. In a smokeless combustion-furnace in which the fresh fuel is fed from underneath below the layer of live fuel, the combination 25 with a combustion-chamber, of a pipe for introducing the fuel into said chamber, means for forcing the fuel through said pipe, a flue for drawing off the combustion-gases and provided with a clinker-collecting trough, an 30 air-conduit surrounding said furnace, openings in the walls of the furnace communicat-

ing with said conduit, and means for operating the fuel-feeding means, the sole of the combustion-chamber being formed as a plane inclined from the fuel-supply pipe toward 35 the flue for drawing off the combustion-gases, substantially as described.

2. In a smokeless combustion-furnace in which the fresh fuel is fed from underneath below the layer of live fuel, the combination 40 with a combustion-chamber having a sloped sole, of a pipe for introducing the fuel into the said chamber, a flue for drawing off the combustion-gases, an air-conduit surrounding the said furnace, openings in the side of 45 the furnace for supplying air to the burning fuel, a piston capable of moving to and fro in the feeding-pipe, a screw rotatably connected to the piston and provided at its outer end with a ratchet-wheel, jaws meshing with 50 the screw and capable of being thrown out of gear with the screw by a counterweight-lever, and means for rotating the ratchet-wheel and regulating its motion, substantially as described.

In testimony whereof I have hereunto set my hand in presence of two subscribing witnesses.

CARL WEGENER.
